(57) **CLAIM**

The ornamental design for a motor vehicle as shown and described.

DESCRIPTION

FIG. 1 is a front and left side perspective view of a motor vehicle showing our new design;

FIG. 2 is a top, front and left side perspective view thereof;

FIG. 3 is a rear and right side perspective view thereof;

FIG. 4 is a top, rear and right side view thereof;

FIG. 5 is a front view thereof, the opposite side being a mirror image of the side shown herein;

FIG. 6 is a left view thereof;

FIG. 7 is a right side view thereof; and,

FIG. 8 is a top view thereof.

The claimed design is shown in full contrast that indicates claimed areas. Half-tone shading indicates areas of unclaimed environmental structure. The broken lines in FIGS. 1, 2, 3, 5, 6, and 7 are included as boundary lines and form no part of the claimed design.
